UNITED STATES PATENT OFFICE

OWEN R. RICE, OF CHICAGO, ILLINOIS, ASSIGNOR TO FREYN ENGINEERING COMPANY, OF CHICAGO, ILLINOIS, A CORPORATION OF MAINE

INWALL COOLING PLATE

Application filed October 22, 1927. Serial No. 227,963.

This invention relates to a cooling plate for use in a blast furnace bosh or stack, and more particularly to a cooling plate having a refractory nose.

5 The conventional purpose of a stack or bosh cooling plate is to preserve certain contour lines within the furnace, the cooling plate being built in the furnace wall and serving in the mass as a part thereof, but having a 10 water chamber connected with inlet and outlet pipes so that water may be circulated therethrough, whereby the cooling plate acts constantly to reduce the temperature of the surrounding walls.

15 It has been found in practice that the contour lines of a furnace ordinarily lack permanence in that the brick is heated to great temperatures in the course of furnace operation, in some instances reaching a temperature 20 of 2000° F., at which temperature the brick loses its mechanical strength and is susceptible in its deteriorated form to being worn away by the abrasive effects of the descending material within the furnace. It has 25 been further found that if the temperature of the brick can be reduced, as with cooling plates, the original mechanical strength of the brick is preserved and the abrasion of the descending material within the furnace is en- 30 dured and consequently the contour lines in the furnace walls are maintained.

In installing cooling plates for this usage, it is not ordinarily desirable to insert the cooling plate all the way through the brick 35 wall so that the nose is flush with the wall on the inside of the furnace, because the soft copper of the plate, if the plate is so placed, soon becomes worn away by the abrasion of the descending material, thereby causing the 40 plate to leak. Hence, it is customary to so place the cooling plate that there is a thickness of brick or wall material between the nose of the plate and the interior wall of the furnace. This thickness of brick differs 45 greatly in different furnaces, ranging anywhere from 4½ inches to 27 inches, and probably averaging about 13½ inches. In installations of this character, and as practiced prior to my invention, there has been no mechanical connection provided between the

nose of the plate and the brick, or protective material for the nose between the plate and the inside surface of the furnace wall. Due to this, when the brick is deteriorated by the action of the heat and the abrasion of the material in the furnace it is free to fall away and expose the nose of the plate with detrimental effects, the plate then becoming leaky and causing trouble and the necessity of being replaced.

55 Accordingly, my invention proceeds upon the principle of establishing a mechanical connection between the nose of the plate, which in cooling plates of the type heretofore known in the art is the inner wall of the water compartment, and the protecting material between the nose and the inner wall surface of the furnace. I accomplished this result by providing a cooling plate having a refractory nose and which nose provides 60 considerable protection for the end of the cooling plate, but in addition I propose to install my cooling plate in the manner which has been heretofore customary, viz, by providing in addition to the refractory material 65 a considerable thickness of brick or other wall material so that at all times the end of the cooling plate is adequately protected.

70 In practicing my invention, the refractory which is placed inwardly of the inner surface wall has no noticeable function during the 75 normal operation of the furnace, i. e., when the inner wall surface is wholly intact, but when the wall portion lying between the refractory and the inner surface has been worn 80 an extent sufficient to threaten an exposure of the cooling plate, then the supported and cooled refractory material at the nose of the plate operates to endure the abrasion of the 85 hot stack where the brick has yielded and in this manner protecting the plate itself and assisting to preserve the original contour of the furnace interior.

90 Accordingly, one of the objects of my invention is to provide a plate of the above 95 described type, having a refractory nose and particularly one having means for maintaining the refractory against accidental displacement at all times.

95 A further object of my invention is to 100

provide mechanical connections between the refractory and the plate, whereby the refractory is maintained in its position, even though the encircling copper walls of the refractory containing socket be destroyed.

5 It is a further object of my invention to provide a construction in which a portion of the water compartment projects into the refractory recess in a manner to be surrounded by the material to hold the material against displacement, and further providing a plurality of irregularly formed projections in the recess and extending in different directions whereby by the intimate engagement with the refractory material they maintain the refractory against accidental displacement.

10 It is a further object to provide in such a device a refractory recess having tapering enclosing walls converging outwardly where-
15 by they aid in resisting accidental displacement of the refractory material.

These and other objects are accomplished by means of the arrangement disclosed on the accompanying set of drawings, in which—

20 25 Figure 1 is a plan cross sectional view of a portion of a furnace wall and a cooling plate constructed in accordance with my invention and taken on the line 1—1 on Figure 4 and looking in the direction of the arrows;

30 35 Figure 2 is a longitudinal sectional view of the plate shown in Figure 1 and taken on the line 2—2 looking in the direction of the arrows;

Figure 3 is a cross sectional end elevation of the device shown in Figure 2; and

40 45 Figure 4 is an end elevational view of the device shown in Figure 2, as seen from the right.

The various novel features of the invention will be apparent from the following description and will be particularly pointed out in the appended claims.

45 Referring to the drawings—

It will be noted that my invention relates to a cooling plate 10, which is built in the wall 11 of a blast furnace and may be disposed in either a vertical or horizontal position (being horizontally disposed in the present disclosure), and is adapted through the inlet and outlet pipes 12 and 13 to provide for the circulation of water through the water chamber or compartment 14. The cooling plate comprises a casing member 15, having the end wall 16, which is larger than the cooling plate and projects beyond the outside edges thereof in a manner to form an abutment overlying the edges of the wall and providing means for attaching the plate to the wall in its desired position. The top wall of the plate is preferably made slightly arched, to add strength in supporting the wall material positioned above the plate. The end plate 16 has bolt holes 17 for accommodating bolts 18 which extend into the wall and secure the plate in position. The

plate in addition is provided with four screw threaded openings 19 for effecting the water connections, such as by pipes 12 and 13, the holes not in use being closed by means of plugs 20. Brackets 21, provided with holes 28, are positioned on the outside of the wall 16 which serve as a means by which the plate may be pulled out when it is replaced. These brackets also act as strengthening ribs and as cooling fins providing greater cooling area 75 80 85 90 95 100 105 110 115 120 125 130

By referring to Figure 4 it will be noted that the plugged holes are centrally disposed and that the inlet and outlet water connections are disposed at diagonally opposite corners. Centrally of the water compartment is a web 21, made integral with the cooling plate casing which terminates short of the end of the plate, whereby the two sides of the water compartment are in communication as at 22, so that the water introduced at one side of the plate, as for instance through pipe 13, may circulate around and flow out of the opposite pipe 12. The casing walls 15 forming the main body of the water compartment are extended as at 23 in a slightly tapering manner so that they form an enclosing sleeve, and with the end wall 24 of the water compartment, a recess for receiving refractory material 25.

Attention is directed to the fact that the wall 24 which forms a partition between the water chamber 14 and the refractory recess is substantially arcuate in shape in one plane as shown in Figure 1 and is tapered in the other plane to form a wedge shaped projection extending into the refractory recess as shown in Figure 2.

Positioned on the arcuate apex of the wall 24 are a plurality of irregularly formed projections 26 which are disposed perpendicularly to the surface from which they project and due to the arcuate nature of the wall the various projections assume a substantially radial relationship.

In forming cooling plates in accordance with my invention, the body of the plate is preferably cast of copper, it being understood, however, that any suitable metal will serve, and in casting the refractory recess the core is formed with a plurality of irregularly cut holes, prior to its introduction into the mould, the holes being located in a position to properly form the projections 26.

When the plate has been completely cast, any suitable refractory material is packad into the refractory recess and is forced there-in to an extent sufficient to cause it to fill the narrow cavities provided between the enclosing shell 23 and the projecting end of the water chamber and to lie in intimate engagement around the projections 26. When the cooling plate has been so filled with refractory material the plate is then placed

in an oven to bake the refractory sufficiently to harden it in its moulded form.

By constructing the refractory nose, as above described, it has been found that a very durable cooling plate is obtained and that the refractory is very securely fastened by means of the mechanical connections provided. It has been found in practice that even though the enclosing shell 23 be partially worn or burned away that the refractory is still maintained in sufficient quantities at the end of the cooling plate to offer a substantial protection thereto.

From the above description it will be readily appreciated that I have provided a cooling plate that is adequately protected, even though the brick or other wall material lying between the plate and inner wall surface of the furnace is worn away during the furnace operation and that in such an event the mechanical connections provided are such that the refractory will be maintained against displacement and will offer substantial protection to the cooling plate at all times.

I claim:

1. An inwall cooling plate comprising a casing having a water compartment and a recessed nose, the wall between said compartment and nose recess being tapered in a manner to provide a portion of said water compartment projecting centrally into said recess, and refractory material in said recess and surrounding said projecting portion of said water compartment.

2. An inwall cooling plate comprising a casing having a water compartment and a recessed nose, the wall between said compartment and nose recess being tapered in two planes in a manner to provide a portion of said water compartment projecting centrally into said recess, and refractory material in said recess and surrounding said projecting portion of said water compartment.

3. An inwall cooling plate comprising a casing having a water chamber and a recessed nose, the wall between said chamber and recess being substantially arcuate in one direction and being provided on its surface with a plurality of irregularly formed projections disposed in a radial manner and extending into said recess, refractory material in said recess, said projections extending into said material, whereby said material is held against accidental displacement.

4. An inwall cooling plate comprising a casing having a water chamber and a recessed nose, the wall between said chamber and recess being substantially arcuate in one direction and projecting in the other direction in a manner to extend partially into said recess, irregularly formed and radially disposed projections on said wall projecting into said recess, refractory material in said

recess surrounding said projections and projecting portion of said water chamber, whereby said material is held by said means against accidental displacement.

5. An inwall cooling plate comprising a casing having a water chamber and a recessed nose, the wall between said chamber and recess being substantially arcuate in one direction and projecting in the other direction in a manner to extend partially into said recess, irregularly formed and radially disposed projections on said wall projecting into said recess, refractory material in said recess surrounding said projections and projecting portion of said water chamber, whereby said material is held by said means against accidental displacement, said recess having tapering walls converging outwardly.

Signed at Chicago, Illinois, this 19th day of Oct., 1927.
